United States Patent Office

Des. 188,667
Patented Aug. 23, 1960

188,685

STATUETTE

Dorothy J. De May, 517 Allenby Ave., Pittsburgh, Pa.

Filed Nov. 16, 1959, Ser. No. 58,368

Term of patent 3½ years

(Cl. D29—23)

Fig. 2.

Fig. 3.

Fig. 1 is a perspective view of a statuette, showing my new design;

Fig. 2 is a rear elevational view thereof; and
Fig. 3 is a side elevational view thereof.

I claim:

The ornamental design for a statuette, substantially as shown.
